US00D752519S

(12) **United States Design Patent**
Bdeir

(10) **Patent No.:** **US D752,519 S**
(45) **Date of Patent:** **** Mar. 29, 2016**

(54) **CONNECTOR FOR MODULAR ELECTRONIC
BUILDING SYSTEM**

(71) Applicant: **littleBits Electronics Inc.**, New York, NY (US)

(72) Inventor: **Aya Bdeir**, New York, NY (US)

(73) Assignee: **littleBits Electronics, Inc.**, New York, NY (US)

(**) Term: **15 Years**

(21) Appl. No.: **29/530,983**

(22) Filed: **Jun. 22, 2015**

(57) **CLAIM**

The ornamental design for a connector for a modular electronic building system, as shown and described.

DESCRIPTION

FIG. 1 is a bottom perspective view of a connector for a modular electronic building system, according to an embodiment;

FIG. 2 is a front view of the connector for a modular electronic building system illustrated in FIG. 1;

FIG. 3 is a rear view of the connector for a modular electronic building system illustrated in FIG. 1;

FIG. 4 is a left side view of the connector for a modular electronic building system illustrated in FIG. 1;

FIG. 5 is a right side view of the connector for a modular electronic building system illustrated in FIG. 1;

FIG. 6 is a bottom view of the connector for a modular electronic building system illustrated in FIG. 1; and,

FIG. 7 is a top view of the connector for a modular electronic building system illustrated in FIG. 1.

The broken lines in the figures show non-claimed portions of the connector for modular electronic building system; the broken lines form no part of the claimed design. In addition, the broken-alternating thick and thin lines illustrate a cross-section of the claimed design and form no part of the claimed design.
